UNITED STATES PATENT OFFICE.

HAROLD GILLESPIE BANDFIELD, OF NEW YORK, N. Y., ASSIGNOR, BY MESNE ASSIGNMENTS, TO WESTERN ELECTRIC COMPANY, INCORPORATED, A CORPORATION OF NEW YORK.

PROTECTOR.

1,222,356

Specification of Letters Patent. Patented Apr. 10, 1917.

Application filed March 8, 1915. Serial No. 12,802.

To all whom it may concern:

Be it known that I, HAROLD GILLESPIE BANDFIELD, a citizen of the United States, residing at New York, in the county of New York and State of New York, have invented certain new and useful Improvements in Protectors, of which the following is a full, clear, concise, and exact description.

This invention relates to protective devices for electric circuits.

In protective devices commonly used in practice, it is customary to separate the electrodes thereof through the medium of a dielectric spacing material. It is the object of this invention to provide a protective device in which the electrodes thereof are held apart and maintained electrically separate without the use of any spacing means.

A protector embodying the features of this invention may comprise a pair of electrodes positioned to oppose each other, one of which electrodes is comprised of bodies of conducting and non-conducting material, and the other of said electrodes is comprised of a conducting member. An air-gap is formed between said electrodes and they are maintained electrically separate by removing a portion of the opposing conducting surface, included between said non-conducting bodies, of either or both of said electrodes.

This invention is illustrated by the accompanying drawing in which: Figure 1 is a front elevation, partly in section, of a protector made in accordance with this invention; and Figs. 2 and 3 are front elevations of modified forms of the protectors shown in Fig. 1.

A protector embodying the features of this invention is composed of a pair of electrodes 4 and 5, positioned to oppose each other and are retained in this position by means of dowel pins 6, 6. The electrode 4 has a portion removed at the ends thereof and bodies 45 of insulating material 7, such as fiber, inserted therein. The electrode 5 comprises preferably a metallic member. A portion of the opposing surface included between the insulation inserts 7, 7 of the electrode 4 is removed. The corresponding surface of the electrode 5 is likewise removed and these recesses form an air-gap between the conducting surfaces of the electrodes 4 and 5. It is obvious that this air-gap may

be regulated by removing a greater or smaller amount of the opposing metallic surfaces bounded by the insulation inserts 7, 7. To more prominently define the air-gap formed between the electrodes 4 and 5, a plurality of notches 8, 8 are made transversely in the electrode 5 at points opposite the inner edges of the insulation inserts 7, 7. The inner corner portion of the inserts 7, 7 is also removed to the same depth as that of the recessed conducting portion of the electrode 4. The function performed by this arrangement tends to eliminate any sparking between the opposing metallic portions of the electrodes 4 and 5 at the point where the conducting and non-conducting portions meet, thereby preventing the consequent carbonization of the insulation inserts 7, 7, which would naturally result in event only the conducting portion was removed.

In the modified forms of protectors shown in Figs. 2 and 3, the air-gap is formed between the opposing electrodes by removing a portion of the opposing surface of only one of said electrodes. In Fig. 2 the air-gap formed between the electrodes 4 and 5 is obtained by removing the opposing conducting surface included between the insulation inserts 7, 7 of the electrode 4. In Fig. 3, the opposing conducting surface and the insulation inserts 7, 7 of the electrode 4 are flushed with each other, while the portion of the electrode 5 bounded by the insulation inserts is removed, thereby creating an air-gap between the conducting surfaces of the two electrodes 4 and 5.

From the above it is apparent that a protector contemplated by this invention is characterized by simplicity of construction and efficiency of operation is obtained by virtue of being able to regulate to a marked degree of fineness the air-gap between the opposing surfaces of the electrodes of the protector, this latter feature being accomplished without the intervention of a dielectric spacing material.

What is claimed is:

1. A protector comprising a pair of electrodes, one of said electrodes comprising a conducting member, the other of said electrodes comprising a body of conducting material and a body of non-conducting material in fixed relation therewith, the opposing conducting surfaces of said electrodes when

placed in opposition to each other being in relatively different planes, whereby an air gap is formed therebetween.

2. A protector comprising a pair of electrodes, one of said electrodes comprising a conducting block having a depressed portion, the other of said electrodes comprising bodies of conducting and non-conducting material in fixed relation to each other and 5 in the same plane, whereby when the electrodes are placed in opposition to each other said depressed portion is electrically distinct from said other electrode and positively separated therefrom by a definite and fixed 10 air gap.

3. A protector comprising a pair of electrodes, one of said electrodes comprising a body of conducting material having sections of insulating material molded therein, the 20 other of said electrodes comprising a conducting member having portions adapted to bear on said insulating sections, whereby

said electrodes are electrically distinct from each other and the opposing conducting surfaces are separated by a definite air gap.

4. A protector comprising a pair of electrodes, one of said electrodes comprising a conducting block having a depressed portion, the other of said electrodes comprising a body of conducting material having insulating material molded therein adapted to provide a bearing surface for said conducting block, whereby when the electrodes are placed in opposition said depressed portion is electrically distinct from said other electrode and positively separated therefrom by a definite and fixed air gap.

In witness whereof, I hereunto subscribe my name this 6th day of March, A. D., 1915.

HAROLD GILLESPIE BANDFIELD.
